Attorney

UNITED STATES PATENT OFFICE.

OSWALD J. LUBBOCK, OF SAN FRANCISCO, CALIFORNIA

SPEINKLER-HEAD.

1,180,517.

Specification of Letters Patent. Patented Nov. 16, 1915.

Application filed July 20, 1915. Serial No. 40,852.

To all whom it may concern:

Be it known that I, OSWALD J. LUBBOCK, a citizen of the United States, residing at San Francisco, in the county of San Francisco and State of California, have invented new and useful Improvements in Sprinkler-Heads, of which the following is a specification.

The present invention relates to sprinkler heads such as are used in automatic sprinkler systems to distribute the water from the pipes of the system in case a fire starts. These sprinkler heads are provided with metal which melts at a comparatively low temperature, and the melting of which releases the water, which escapes under pressure, and is distributed by the sprinkler.

The principal object of the invention is to provide a sprinkler head in which the removal of the device for restraining the water will be effected with greater certainty than heretofore upon the fusing of the metal.

Again, very often by far the greater part of the damage is caused by the flow of water after the fire has been put out and before the water can be shut off.

A further object then of the invention is to provide means, not unduly conspicuous in appearance, whereby the flow of the water can be shut off easily and quickly.

My invention also resides in the novel construction, combination and arrangement of parts hereinafter more fully specified and particularly pointed out in the claims.

In the accompanying drawing, Figure 1 is a side view of my improved sprinkler head; Fig. 2 is a longitudinal section of the same; Figs. 3, 4, and 5 are detail views of parts thereof; Fig. 6 is a side view partly in section of a modified form of sprinkler head.

Referring to the drawing, 1 indicates a pipe of a sprinkler system. Into said pipe is screwed, as shown at 2, the lower tubular part of my improved sprinkler head, the opening in which converges to the top, as shown at 3, and terminates in a valve seat 4. On said seat is a thin disk 5 of non-corrodible metal, such as copper or German silver, and, securing said disk upon said seat, is a cap valve 6, having a flange 7 surrounding the seat and a central conical enlargement or boss 8 upon its upper surface. Upon the apex of said boss is supported a sectional strut 9, comprising two strut sections 10, separated on a plane through the axis of the strut, said strut having at the top and bot-

tom conical recesses 11 and 12. The apex of the conical enlargement 8 of the valve fits in the lower recess 12, while in the upper recess 11 fits the conical lower end of a 60 presser bar 13. Said strut sections are held together by a sectional plate 14, formed of two sections 15 of brass or similar metal united by intervening strips 16 of easily fusible solder. Said plate is formed with a 65 central hole through which the strut passes, and the strips 16 extend on opposite sides of said hole. The plate rests upon flanges 17 carried by the strut sections.

The presser bar slides in guides 18 depending from a yoke 19 forming part of the sprinkler head. When the parts are placed in working position, with the valve 6 on its seat 4, and the strut 9 on the valve 6, the presser bar is lowered until its lower end enters the conical recess 11 in the top of the strut, and then a screw 20 is screwed into an upper threaded recess in the yoke, its lower end bearing down upon the upper end of the bar, until a considerable pressure has 75 been imparted by said screw to said bar and is borne by the strut. When the desired pressure has been attained, a rivet 21 is driven through the yoke and through the screw 20. The strut sections are thus subjected to a central bursting strain, by reason 80 of being compressed between the conical enlargement of the valve and the conical lower end of the presser bar.

In the event that a fire occurs and becomes 90 hot enough to melt the easy fusible solder 16, the plate sections then separate, and the strut sections also separate, owing to the bursting strain to which they are subjected. The pressure of the water then violently 95 forces up the valve 6 and disk 5, and these parts are pushed to one side by the rush of the water.

Around the lower part of the presser bar is secured a rubber valve 22, the lower surface of which is conical and continuous with the conical lower end of the presser bar, and above said valve fingers 23 extend radially from a plate 24 secured to the presser bar above said valve, said fingers forming 100 a distributor, the water being forced against the under side of said fingers and deflected thereby to a considerable distance from the sprinkler head. The sides of the yoke would ordinarily prevent the water from being deflected to the part of the room behind said sides, and in order to prevent this occurring 105 110

and to render uniform the distribution of the water, the distributing fingers are twisted, as shown in Fig. 1. Said rubber valve is for the purpose of closing the water after the sprinkler head has served its purpose, and to this end there is also provided a lever 26 which is pivoted at one end, as shown at 27, to a side of the yoke, extends through slots 28 in the yoke and 29 in the presser 10 bar 13, and is formed at the other end with a hook 30. Said hook can readily be engaged by any suitable implement having a long handle, and the presser bar can thereby be pressed down until the rubber valve 15 closes against the seat 4 and effectually shuts off the water. It can either be held in such position by hand or can be tied or otherwise fastened in place.

In the form of the invention shown in 20 Fig. 6 the lever for closing off the water is omitted and in such case the distributor is placed at the top of the yoke instead of on the presser bar. The rivet is driven through the presser bar when the latter has been 25 moved into proper position by a screw 31 screwed through the top of the yoke.

I regard as novel and as part of my invention the arrangement whereby a bursting strain is applied to the center of the 30 sectional strut.

I am aware that it has been proposed to 35 separate strut sections by means of the pressure from a spring plate applied to said plate at its center, but such pressure is only applied by the edge of the plate, and is not as effective as when applied, as in my invention, at all points of a conical surface. Furthermore I apply such pressure upon a 40 conical surface both at the top and bottom of the strut. When pressure is applied at one end only of the strut, the friction of the other end against the supporting surface is so great as to render it difficult to separate the strut sections. This objection is over- 45 come when the pressure is applied at both ends. Furthermore I hold the strut sections together by means of a plate consisting of sections held together by easily fusible metal along their edges, as contrasted with prior 50 devices in which the strut sections are held together by easily fusible solder applied to the broad surfaces of a band. In such case there is a very great probability of the parts 55 of the retainer, which are held together by the easily fusible solder, not separating when the solder is melted, on account of the adhesion thereof caused by reason of corrosion of the surfaces, said surfaces being very considerable. By employing a plate, the com- 60 paratively thin or narrow edges of which are held together by easily fusible solder, the above danger of inoperativeness through corrosion is avoided. I believe I am also the first to provide an emergency stopper for 65 automatic sprinklers which consists merely

of a hooked lever which can be engaged by a suitable implement having a long handle. Prior automatic sprinkler heads have not been provided with any device especially intended for the purpose of shutting off the 70 water after the sprinkler head has performed its office. Consequently, it has been necessary to provide special and somewhat complicated implements for shutting off the water. By providing a hooked lever in the 75 sprinkler head itself, it is not necessary to have any special tool for shutting off the water, provided only that it has at one end means for engaging and pulling down the hooked lever. I also regard as new and patentable the twisted fingers of the distributor for rendering uniform the distribution of the water as well as the rubber conical valve beneath the distributor for shutting off the 80 water.

85 I claim:—

1. A sprinkler head having a valve seat, a valve on said seat and having a conical enlargement on its upper surface, strut sections forming a strut having conical recesses 90 at the top and bottom, the plane of separation of said strut sections extending through the apices of said conical recesses, a plate having a hole through which said strut extends and comprising plate sections separated from one another on a plane extending through said hole, easily fusible solder connecting said plate sections, the conical enlargement engaging the recess in the bottom, a presser bar having a conical lower end 100 engaging the recess in the top, means for limiting the upward movement of said bar, and a distributor above the valve seat.

2. A sprinkler head having a valve seat, a valve on said seat and having a conical enlargement on its upper surface, strut sections forming a strut having conical recesses 105 at the top and bottom, the plane of separation of said strut sections extending through the apices of said conical recesses, a plate 110 having a hole through which said strut extends and comprising plate sections separated from one another on a plane extending through said hole, easily fusible solder connecting said plate sections, the conical enlargement engaging the recess in the bottom, a presser bar having a conical lower end 115 engaging the recess in the top, a vertical guide for said bar, means for limiting the upward movement of said bar, a rubber 120 conical valve on the bar below the distributor, a distributor above the valve seat, and a lever pivoted at one end to the sprinkler head and engaging the bar to press the valve down to its seat and having a hooked free 125 end.

3. A sprinkler head having a valve seat, a valve on said seat and having a conical enlargement on its upper surface, strut sections forming a strut having conical recesses 130

at the top and bottom, the plane of separation of said strut sections extending through the apices of said conical recesses, a plate having a hole through which said strut extends and comprising plate sections separated from one another on a plane extending through said hole, easily fusible solder connecting said plate sections, the conical enlargement engaging the recess in the bottom, 10 a presser bar having a conical lower end engaging the recess in the top, a vertical guide for said bar, means for limiting the upward movement of said bar, a rubber conical valve on the bar below the distrib-

uter, a distributor above the lower end of 15 the presser bar having outwardly extending fingers, certain of said fingers being twisted, and a lever pivoted at one end to the sprinkler head and engaging the bar to press the valve down to its seat and having a 20 hooked free end.

In testimony whereof I have hereunto set my hand in the presence of two subscribing witnesses.

OSWALD J. LUBBOCK.
